UNITED STATES PATENT OFFICE.

JULIAN M. CASE, OF NORTH LANSING, MICHIGAN.

DESIGN FOR PLATE OF ALARM-LOCKS.

Specification forming part of Design No. 5,069, dated July 4, 1871.

To all whom it may concern:

Be it known that I, JULIAN M. CASE, of North Lansing, in the county of Ingham and State of Michigan, have invented and produced a new and original Design for Plate for Alarm-Locks; and I do hereby declare that the following is a full, clear, and exact description of the same.

The nature of my design is fully represented in the accompanying photographic illustration, to which reference is made.

I claim as my invention—
The design for plate for alarm-lock, as shown.
In testimony that I claim the above I have hereunto subscribed my name in the presence of two witnesses.

JULIAN M. CASE.
